(57) **CLAIM**

The ornamental design for a water filter, as shown and described.

DESCRIPTION

FIG. 1 is a front view thereof;

FIG. 2 is a rear view thereof;

FIG. 3 is a left view thereof;

FIG. 4 is a right view thereof;

FIG. 5 is a top view thereof; and,

FIG. 6 is a perspective view of a water filter according to the present invention.

1 Claim, 4 Drawing Sheets

FIG. 1**FIG. 2**

FIG. 3**FIG. 4**

FIG. 5

FIG. 6
